UNITED STATES PATENT OFFICE.

JOHN HEARNE, OF NEW YORK, N. Y.

GAS-PURIFIER.

SPECIFICATION forming part of Letters Patent No. 433,126, dated July 29, 1890.

Application filed March 3, 1890. Serial No. 342,410. (No model.)

To all whom it may concern:

Be it known that I, JOHN HEARNE, of New York, in the county and State of New York, have invented a certain new and useful Improvement in Gas-Purifiers, of which the following is a specification.

My improvement relates to so-called "purifier-boxes," in which are placed chemicals, over or through which illuminating-gas is passed in order to purify it.

I will describe a purifier-box embodying my improvement in detail, and then point out the novel features in claims.

In the accompanying drawings, Figure 1 is a vertical central section through two compartments of a box and the outlet-pipe common thereto. Fig. 2 is a top plan view of the same, the cover of the box being removed and the tray-holder being removed from one of the compartments.

A designates the body portion of the box, shown as of oblong form. It may be of any desired depth and has an open top.

B designates the cover for the box. The edges b of this cover, when the cover is in position upon the body, rest in a water lute or seal, formed in a trough or gutter b' extending about the box near the top of the latter. The trough b' has a closed bottom, formed by a flange b², extending horizontally from and about the body A. One of its side walls is formed by the body A and the other by side pieces b³, which extend upwardly from the flange b² and somewhat above the top of the body A.

The construction thus far described is not new.

C designates a trough or gutter which divides the upper part of the body A into two approximately square portions or compartments a a'. The ends of this trough open into the trough b'. Water in the troughs b' C will therefore be in communication and at the same level in both. Gas enters at the ports c in the bottoms of the portions a a', and, in the example of my improvement shown, finds exit through a pipe c', extending upwardly from the bottom of the gas-holder intermediate between the portions a a' to a point above the water-level in the trough C. The outlet-pipe c', as it extends upwardly, gradually changes

from a circular to an elongated form in cross-section, thereby economizing space between the portions a a' and affording ample space for receiving the gas which passes up through 55 the trays.

D D' designate tray-holders, in which trays or grids D², which may be of ordinary construction, are supported upon internal ribs or flanges d, extending horizontally about the 60 interior of the holders. Chemical material adapted to purify the gas is placed upon the trays or grids. The tray-holders D D' are of approximately the same shape as the portions a a' and extend with a loose fit into them, 65 and, when in position, nearly to the bottom of the box A. They have open tops and bottoms. Near their tops the said tray-holders are provided with horizontally-extending flanges d' upon all sides. From the outer 70 edges of the flanges d', flanges d² extend downwardly upon all sides. When the holders are in position the sides of the portions a a' extend into the space formed between the flanges d² and the sides of the holders, and the flanges 75 d' of the holders extend downwardly into the water lutes or seals formed in the troughs or gutters b' C. Between the flanges d² and the side pieces b³ is sufficient space to receive the sides of the cover B when the latter is placed 80 in position. Gas entering through the ports c will pass upwardly about and over the chemical material placed upon the trays in the holders D D', and will, after being thus purified, 85 pass outwardly through the pipe c'.

When the chemical material upon the trays or grids D² becomes exhausted and needs revivifying or renewing, or when from any other cause it is desired to remove the chemical material from the portions a a', I lift out the 90 tray-holders D D', and with them the trays D² and the chemical material. This is conveniently effected by means of any suitable tackle-engaging rings g with which the tray-holders are provided. This may be effected 95 very quickly and avoids all shoveling of the chemical material from the trays or compartments, as is now the common practice. The tray-holders having been lifted out, other tray-holders, which, in the intervals of charging, 100 have been refilled with fresh material, may be as quickly lifted into position. The operation

- of the purifier may in this way be made practically continuous, being interrupted only for a sufficient time to lift out one set of tray-holders and trays and insert a fresh set. The 5 tray-holders which have been lifted out may be conveyed away in any suitable manner and the material dumped from the trays where desired. The trays may then be refilled ready for a fresh charge.
- 10 Although I have shown and described two tray-holders, I may of course use any desired number.
- 15 It will be seen that by my improvement very much time and labor are saved, the great 15 danger of asphyxiation which laborers experience who enter purifiers as ordinarily constructed is wholly avoided, a simple and effective seal is provided which prevents the escape of gas around the tray-holders, a free 20 outlet afforded, and, because of the communication between the water-lute which seals the tray-holders and the water-lute which seals the cover of the box, should any escape

take place around the tray-holders it could easily be detected from the outside. 25

What I claim as my invention is—

1. In a gas-purifier, the combination, with the body portion of a box surrounded near its top with a water seal, of a cover adapted to extend into said water seal, and a removable tray-holder supported in said box beneath the cover and provided with a flange also extending into said water seal, substantially as set forth. 30

2. The combination, with a box and purifying compartment within the box, of a water lute located between two purifying compartments, and a gas-outlet pipe extending from the bottom of the gas-holder up within the water lute and having its upper end transversely elongated, substantially as set forth. 35 40

JOHN HEARNE.
